(57) CLAIM

I claim the ornamental design for a fishing flasher, as shown and described.

DESCRIPTION

FIG. 1 is an isometric view of a fishing flasher showing my design;

FIG. 2 is a top view thereof, it being understood that the opposite side not shown is a mirror image thereof;

FIG. 3 is a rear view thereof;

FIG. 4 is a right side elevation view thereof, it being understood that the opposite side not shown is a mirror image thereof;

FIG. 5 is a front view thereof; and,

FIG. 6 is a perspective view of the fishing flasher shown in use.

The broken lines shown represent unclaimed subject matter and form no part of the claimed design.

1 Claim, 4 Drawing Sheets
